UNITED STATES PATENT OFFICE.

HOWARD J. TREGANZA, OF NEW YORK, N. Y., ASSIGNOR TO THE ANSONIA CLOCK COMPANY, OF NEW YORK, N. Y., A CORPORATION OF CONNECTICUT.

CLOCK.

1,103,453.

Specification of Letters Patent.

Patented July 14, 1914.

Application filed March 14, 1913. Serial No. 754,294.

To all whom it may concern:

Be it known that I, HOWARD J. TREGANZA, a citizen of the United States, and resident of the borough of Brooklyn, in the city and 5 State of New York, have invented a new and useful Improvement in Clocks, of which the following is a specification.

My invention comprises a novel clock switch arranged to permit or prevent the 10 striking of the bell hammer, the switch being slidably mounted on the clock case and movable in a right line toward and away from the clock face.

The object of this invention is to provide 15 a switch of the above character which will be novel in construction and operation; which will be very simple and inexpensive to manufacture; and which will be mounted on the case entirely separate from the other 20 members of the clock.

A practical embodiment of my invention is represented in the accompanying drawings, in which—

Figure 1 represents an alarm clock in top 25 plan with my invention applied thereto, a portion of the bell and handle being broken away to disclose the alarm and striking hammer, and the opening in the case through which they project, Fig. 2 is a detail back 30 view of the clock, Fig. 3 is a detail section taken in the plane of the line A—A of Fig. 1, Fig. 4 is a detail section taken in the plane of the line B—B of Fig. 2, and Fig. 5 is a detail section taken in the plane of 35 the line C—C of Fig. 2.

The clock case is denoted by 1, a portion 40 of its works by 2, its bell by 3 and its time and alarm hammers by 4 and 5, respectively. These hammers project through an opening 6 in the case and are operated to strike the bell in the usual manner.

The switch comprises a slide member 7, a stop member 8, and a handle member 9. A track for the slide member 7 of the switch 45 is provided, in the present instance by striking up a portion of the case to form an elongated recess 10, within which recess the slide member 7 of the switch is fitted to be reciprocated.

An elongated slot 11 is cut through the 50 wall of the recess, within which slot the shank 12 which connects the handle member 9 with the slide member 7 is fitted to slide. The slide member 7 of the switch 55 is preferably bowed so as to increase the

frictional engagement of the slide member and the handle member with the case to retain the switch in its adjusted positions against unintentional displacement. The stop member 8 projects from the slide member 7 a sufficient distance to permit its free end to be brought into and out of the path of the alarm hammer 4 to prevent or permit the alarm hammer to strike the bell 3 as desired.

The slide member 7 and the stop member 8 are preferably formed integral from a single piece of metal thus materially simplifying the switch.

By forming the track for the slide member by striking up a portion of the case, a very simple and inexpensive means are provided for guiding the slide member in its movements.

What I claim is:—

1. In a clock, a bell hammer and a switch 75 slidably mounted on the case and movable in a straight path at right angles to the clock face and across the path of and directly engaging the hammer.

2. In a clock, a bell hammer and a switch 80 slidably mounted on the case, comprising interior stop and slide members and an exterior handle movable in a straight path at right angles to the clock face to bring the 85 stop member across the path of the hammer to directly engage it.

3. In a clock, a case having an elongated 90 recess and a slot through the wall of the recess, a bell hammer and a switch comprising a member slidable in said recess, a stop member inside the case and a handle member outside the case, operable to move the slide member into position to bring the stop member across the path of and directly 95 engaging the hammer.

4. In a clock, a case having an elongated 100 recess and a slot through the wall of the recess, a bell hammer and a switch comprising a member slidable in said recess, a stop member inside the case and a handle member outside the case, operable to move the slide member into position to bring the stop member across the path of and directly 105 engaging the hammer, the slide member being bowed to increase the frictional engagement of the slide and handle members with the case.

5. In a clock, a case having portions struck 110 up from the inside to form an elongated

recess and a slot cut through the wall of the recess, a bell hammer and a switch comprising a member slideable in said recess, a stop member inside the case and a handle member outside the case operable to move the slide member into position to bring the stop member across the path of and directly engaging the hammer.

In testimony, that I claim the foregoing as my invention, I have signed my name in ¹⁰ presence of two witnesses, this twelfth day of March, 1913.

HOWARD J. TREGANZA.
